US00D999792S

(12) **United States Design Patent** (10) Patent No.: **US D999,792 S**
(45) Date of Patent: **** Sep. 26, 2023**

(54) **CABIN FOR CONSTRUCTION MACHINE**

(71) Applicant: **Hitachi Construction Machinery Co., Ltd.**, Tokyo (JP)

(72) Inventors: **Katsumi Usami**, Tsuchiura (JP); **Atsushi Ninomiya**, Tokyo (JP); **Yusuke Daimon**, Tsuchiura (JP); **Masaru Oda**, Tokyo (JP); **Kazuo Ishida**, Ryugasaki (JP); **Yoshihiro Itou**, Ryugasaki (JP); **Shoroku Kawahara**, Ryugasaki (JP)

(73) Assignee: **Hitachi Construction Machinery Co., Ltd.**, Tokyo (JP)

(**) Term: **15 Years**

(21) Appl. No.: **29/789,961**

(22) Filed: **Oct. 27, 2021**

(30) **Foreign Application Priority Data**

Apr. 28, 2021 (JP) ..... 2021-009053 D

(51) **LOC (14) Cl.** **15-03**

(57) **CLAIM**

The ornamental design for a cabin for construction machine, as shown and described.

DESCRIPTION

FIG. 1 is a first perspective view of a cabin for construction machine showing our new design;

FIG. 2 is a second perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

1 Claim, 8 Drawing Sheets
